UNITED STATES PATENT OFFICE

2,465,650

TRACK DOOR OPERATING MECHANISM

John Vincent Jamison, Jr., Hagerstown, Md., assignor to Jamison Cold Storage Door Company, Hagerstown, Md., a corporation of Maryland

Application September 17, 1945, Serial No. 616,847

1 Claim. (Cl. 268—14)

1

The invention has to do with an insulated door closure unit for rooms which are to be maintained at refrigerating temperatures; rooms which are air-conditioned and maintained at high and even temperatures; and rooms requiring acoustical control to dampen noises incident to the testing or operating of mechanical devices. The products and devices moved into and out of the rooms of the above type are often of considerable weight and volume, making it necessary to install tracking above the insulated entrance door on which a carriage or trolley equipment is mounted for conveying the products or devices into and out of the room through the entrance doorway. The entrance door must of necessity swing beneath the tracking and a space provided above the entrance doorway for the tracking. The opening in the wall of the room for the insulated door closure unit is made of sufficient size not only to provide for the entrance door, but for the open space thereabove for the tracking.

The entrance door frame and casing are extended so as to close this opening above the entrance door except a relatively small space immediately adjacent the tracking, forming what is commonly called a track port. This track port is provided with a track door which is hinged at the top and which is raised and lowered by mechanical linkage to the entrance door so that when the latter is swung to open position the track door will swing upwardly to a minimum of 90° and remain in such position as long as the entrance door stands open, and will be closed by such mechanical mechanism when the entrance door is swung to closed position. In order to maintain an air-tight and sound-tight contact, this track door operating mechanism must tightly seal the track door against the frame head casing of the entrance door, but at the same time must have flexibility of contact with the frame to take care of wear and tear of the gaskets provided for the sealing of the track port door, and similar wear and tear on the gaskets of the entrance door.

An object of the invention is to provide a track door operating mechanism wherein the linkage connection between the entrance door and the track port door includes yieldable means so that the track port door may be tightly closed and sealed and not in any way interfere with the closing and tight sealing of the entrance door.

In the drawings:

Figure 1 is a view partly in section and partly in side elevation showing a door operated mechanism for the track port door with said track port door in closed position and the entrance door also in closed position;

Figure 2 is a view similar to Figure 1 but showing the track port door at substantial open position and the entrance door partially open.

5

Figure 3 is a sectional view on the line 3—3 of Figure 1.

Figure 4 is a view of a portion of the track door showing the same in closed position and the track in section.

10

The invention has to do with an insulated door closure unit for rooms used for the purposes above described. The closure unit includes a door frame or casing having an extension which completely fills the opening provided for entrance to and from the room. Extending across the door frame is a head frame casing which is provided with an opening for a trackway. This opening extends into the doorway of the main entrance or walk-in door so that products and devices moved into and out of the room may be suspended from a suitable carriage or trolley moving along the trackway. The closure unit includes a main entrance door and a track port door which are so interconnected that when the entrance door is closed the track port door will also be closed and tightly sealed, and likewise when the entrance door is open, the track port door will be moved to full open position and remain in said open position as long as the entrance door is open.

15

Referring more in detail to the drawings where-in one embodiment of the invention is illustrated, a portion of the head frame casing is indicated at 10. This frame head casing is provided with a relatively small opening formed therethrough and extending all the way to the bottom of the head casing, through which opening extends a track T. This is the track on which the carriage or trolley carrying the product or device moves into and out of the room. An entrance door D is suitably hinged to the door casing. The rear panel of the door engages a gasket carried by the rabbet H. The front panel 14 of the door carries a gasket 17 which engages the door casing. Thus it is that the door, when closed, tightly seals the entrance opening.

20

The track port doorway is closed and sealed by a door D' which is hinged at 19 to a suitable bracket 18 attached to the frame casing. The door is pivoted to swing about a hinge connection at the upper end of the door and when moved to an open position, as shown in Figure 2, it will swing to an angle of at least 90° so as not to interfere with the travel of the carriage on the track.

25

The track port door is moved to and from closed position by a linkage and cam mechanism which, in part, is carried by the entrance door. This linkage for controlling the track port door includes a bracket 22 which is attached to the inner or under face of the track port door D'. Pivotedly connected to this bracket is an arm 23. Said arm is mounted between ears 24 and 25 passing through the bracket. Passing through

the ears is a hollow pintle 26. The arm 23 is provided with spaced members 27 and 28 and these members pivot on the pintle 26.

A spring 29 encircles the pintle 26. The end 30 of the spring bears against the bracket and the end 31 of the spring bears against the arm 23. This spring is placed under tension and tends to turn the arm 23 in a clockwise direction.

A link 32 is pivoted at 33 to the arm 23. Attached to one side of the frame forming the track port door opening is a plate 34. A lever arm 35 is pivoted at 36 to this plate. The upper end of the lever arm is pivoted at 37 to a link 32. This lever arm 35 carries a roller 38 which is adapted to engage between the inclined cam walls 39 and 41 carried by a bracket 40 fixed to the upper edge of the entrance door. In Figure 1 the entrance door is closed and likewise the track door. When the entrance door is swung away from its closed position, the bracket 40 moving therewith will cause the inclined cam wall 41 to engage the roller 38 and this will swing the lever arm 35 in a clockwise direction, and the lever arm through the link 32 will move the track door to open position as shown in Figure 2. As the entrance door continues to swing toward open position, the inclined cam wall 41 will move out of contact with the roller 38. It is noted that the lever arm 35 and the link 32 are moved to a position so that the pivotal connection 37 between the two is beyond the line drawn through the pivotal connection of the link 32 to the arm 23 and the pivot connection of the lever arm 35 to the plate 34. In other words, the door is held open by the toggle lock between this lever arm and the link 32.

When the entrance door is moved toward the closed position, the inclined cam wall 39 will contact with the roller 38 and will force the arm 35 to turn in a counterclockwise direction, and this will break the toggle and pull the track port door to the closed position. The inner ends of the inclined cam walls are curved outwardly away from each other to facilitate the entrance of the roller 38 between these cam walls. When the track port door is tightly closed, the entrance door can continue to move to full closed position by reason of the fact that a pull on the link 32 after the port door is closed, will swing the arm 23 in a counterclockwise direction as viewed in Figure 1. Swinging movement is resisted by the spring 29. The arm 23 and the spring associated therewith form a yieldable connection between the link 32 and the track port door.

A track port door D' or the casing is provided with sealing gaskets 20 extending along the sides and top of the opening closed by the track port door. There is a slot 21 in the door which is of sufficient width so that the track port door can move to closed position without removing the track.

Secured to the inner face of the track port door is a flexible sheet of gasket material 20a. This flexible sheet of gasket material extends a short distance below the lower edge of the track port door, and is provided with a slit 20b disposed centrally of the slot in the track port door. When the track port door moves to closed position, the track T will enter this slit so that there is a substantial sealed connection between the track door and the head frame casing 10, also between the track door and the upper edge of the entrance

door in the region of the opening through the head casing.

When the parts are first installed, both doors may close and seal simultaneously. It is preferred, however, to install the parts so that the movement of the entrance door towards closed position will effect a tight closing of the auxiliary or track port door before the entrance door is tightly closed and then through this yieldable connection the entrance door can continue to move until it is tightly sealed.

When the entrance door is open the opposed inclined cam wall 41 will engage the roller 38 and force the lever arm 35 to swing in a clockwise direction. This will, through the link 32, force the track port door to full open position as shown in Figure 2. The arm 23 is limited in its movement toward the track port door by contact with the bracket 22. The track port door will, therefore, be positively opened but yieldingly closed by a pull resisted by the spring 29.

It is obvious that if the gasket wears, this will not in any way disturb the tightness of the closing of the doors as the arm 23 is moved away from the door resisted by the spring for the closing of the track port door, and therefore this spring connection will take up any wear and ensure that the track port door will be tightly closed by the movements of the entrance door. Furthermore, the track port door will not at any time prevent the entrance door from fully closing and tightly sealing the entrance doorway to the room.

While the cam means for actuating the linkage between the doors is mounted on and movable with the entrance door, it will be understood that other arrangements may be provided for swinging the linkage, but it is essential that this means shall be so connected to the entrance door that the movement of the entrance door toward and from closed position will produce like movements of the track port door toward and from its closed position.

It is obvious that minor changes in the details of construction and arrangement of parts may be made without departing from the spirit of the invention as set forth in the appended claim.

I claim:

In an insulated door closure unit the combination of an entrance door, a track port door, and means operated by the entrance door for opening and closing the track port door including a bracket attached to the track port door, an arm pivoted to said bracket, a link connected to said arm, spring means for moving the arm toward the track port door, a lever mounted on the track port door frame and pivoted to said link, and cam means operated by the entrance door when moved to closed position for swinging said lever to close the track port door by a pull on said link restrained by said spring and for opening the track port door when the entrance door is opened.

JOHN VINCENT JAMISON, JR.
